E. HOE AND CO., OF NEW YORK, N. Y., A CORPORATION OF NEW YORK.

ROTARY FOLDING MECHANISM.

1,116,495.

Specification of Letters Patent.

Patented Nov. 10, 1914.

Application filed March 20, 1909. Serial No. 484,783.

To all whom it may concern:

Be it known that I, LOUIS A. SCHMIDT, a citizen of the United States, residing at New York, county of Kings, and State of New York, have invented certain new and useful Improvements in Rotary Folding Mechanisms, fully described and represented in the following specification and the accompanying drawings, forming a part of 10 the same.

This invention relates to certain improvements in rotary folding mechanisms.

In the operation of modern rotary printing machines, especially those intended for 15 newspaper work, where a large product and consequent rapidity of operation is required, it has been found that the speed of the printing mechanism, practically considered, is determined by the speed of the 20 folding apparatus. In the application of William Spalekhaver, Serial No. 472,393, filed Jan. 15, 1909, there is disclosed a folding mechanism comprising a cylinder having two rotary folding blades mounted 25 therein, these blades being carried on shafts. On these shafts are mounted gears which mesh with the teeth of an internally toothed ring, so that as the cylinder rotates, the folding blades rotate, the gearing being so 30 proportioned as to cause each folder blade to fold off at the same point in the rotation of the cylinder. Folding mechanism of this character has a high efficiency as to the 35 number of papers produced per hour. It has been found in practice, however, when the folding cylinder is running at the speed necessary to develop its high efficiency, say three hundred revolutions or more per minute, that the centrifugal force developed 40 tends to cause the folding blade carrying shafts to bind in their bearings, thus producing friction and heat. Further, since the shafts cannot, of course, fit their bearings with a driving fit, there is opportunity for 45 a slight play of the shafts with respect to the bearings which interferes to some extent with the smoothness of operation desirable when mechanism is to run at the high speeds required. It will be understood 50 that in these mechanisms the folding blade carrying shafts usually make three revolutions to one of the cylinder, so that these shafts may make from nine hundred revolutions a minute up, according to the speed of 55 the cylinder. Further, it is obvious that

with any wear in the bearings, the opportunity for play is considerably increased.

It is the object of this invention to produce a rotary folding mechanism employing a rotary carrier having a plurality of folding blade carrying shafts and blades in which means shall be provided for controlling the effect on the folding blade shafts of the centrifugal force developed in the revolution of the carrier, thus overcoming 60 the tendency of the shafts to bind in their bearings and prevent play and wear.

With this and other objects not specifically referred to in view, the invention consists in certain constructions and in certain parts, 65 improvements and combinations as will be hereinafter fully described and then specifically pointed out.

In the accompanying drawings—Figure 1 70 illustrates in end elevation a folder mechanism constructed in accordance with the invention. Fig. 2 is a side elevation, partly in section, of one end of the folder mechanism illustrated in Fig. 1.

Referring to the drawings, 1 indicates a 75 rotary carrier mounted on a shaft 2, this shaft being supported in bearings 2' mounted in the frame 4. The carrier will be provided with a plurality of sheet receiving surfaces. In the construction shown, the 80 carrier has two such surfaces 5, 6. Means will usually be provided for holding the sheets to be folded on the surfaces, these means, in the particular construction shown, comprising pins 7, 8 which may be mounted 85 and operated in the manner usual in such constructions. If desired, the carrier may be formed as one of a pair of cutting cylinders, the carrier illustrated being adapted for this purpose by providing it with the usual cutting 90 woods 9.

Constructions embodying the invention will include a plurality of rotary folding blades. In the particular construction illustrated, these blades are indicated at 10, the 95 blades being shown as mounted on shafts 11. While the bearings for these shafts may be variously supported, they will, in the best constructions, be mounted in the cylinder heads; the bearings illustrated being marked 100 12. The folder blade carrying shafts will, in constructions embodying the invention, be caused to rotate around their own axes as the carrier rotates. In the best constructions 105 embodying the invention, this rotation of the 110

folder blade carrying shafts will be effected by gearing. In the construction illustrated, each of the shafts 11 is provided at one end with a hub 13, this hub being made fast to the shaft in any suitable manner, as, for instance, by means of a set screw 14. To the flange of each hub 13 is secured a ring gear 15, the attachment being effected in any suitable manner, as by screws 16. These gears 15 are in mesh with an internally toothed ring gear 16' secured to the frame in any suitable manner, as, for instance, by brackets and screws, one of which is indicated at 17.

Constructions embodying the invention 15 will include means for controlling the effect on the folding blade shafts of the centrifugal force developed by the rotation of the cylinder. While these means may be varied, in the particular construction illustrated, there is secured to the end of each shaft 11 a circular bearer 18, the diameter of this bearer being equal to the pitch circle of the gear 15. These bearers, in the construction illustrated, run on a circular 20 track, the diameter of the circle inclosed by this track being equal to the pitch circle of the internal gear 16'. This track may be mounted in any suitable manner. In the particular construction illustrated, this 25 track, marked 19, is mounted in a recess in the gear 16', the parts being secured together in any suitable manner, as, for instance, by uniting them with a driving fit. The proportions of the gearing will be such 30 as to cause the folding blades to fold off at the same point, and in the particular construction illustrated, these blades tuck off between a pair of intergeared folding rolls 20, these rolls being driven in the usual 35 manner from a gear 21 on the cylinder.

With the construction as described, it will be understood that the bearers coöperating with the circular track will firmly hold the shafts against the centrifugal force developed in the rotation of the cylinder 1 and will overcome any tendency of the shafts to bind in their bearings. Further, since the pitch circles of the bearers and track correspond with the pitch circles of the gearing, 45 a rolling contact between the bearers and the track is assured, and at the same time the shafts are securely held against any play and wear in the bearings is prevented, the construction thus conducing to that 50 smoothness in operation which is desirable in high speed mechanism.

Changes and variations may be made in the construction by which the invention is carried into effect. The invention is not, 55 therefore, to be confined to the particular construction hereinbefore shown and described.

What is claimed is:—

1. The combination with a rotary carrier 60 having a plurality of sheet receiving sur-

faces, of a plurality of folding blades, shafts on which the blades are mounted, and means for controlling the effect on the shafts of the centrifugal force developed in the rapid rotation of the carrier throughout the entire revolution of the carrier, whereby the shafts are prevented from binding in their bearings.

2. The combination with a rotary carrier 65 having a plurality of sheet receiving surfaces, of a plurality of folding blades, continuously rotating shafts on which the blades are mounted, bearings for the shafts, and means for controlling the effect on the shafts of the centrifugal force developed in the rapid rotation of the carrier, whereby the shafts are prevented from binding in their bearings.

3. The combination with a rotary carrier 70 having a plurality of sheet receiving surfaces, of a plurality of folding blades, shafts on which the blades are mounted, bearings for the shafts, and means for holding the shafts against the centrifugal force developed by the rapid rotation of the carrier throughout the entire revolution of the carrier.

4. The combination with a rotary carrier 75 having a plurality of sheet receiving surfaces, of a plurality of folding blades, continuously rotating shafts on which said blades are mounted, bearings for the shafts, and means for holding the shafts against the centrifugal force developed by the rapid rotation of the carrier.

5. The combination with a rotary carrier 80 having a plurality of sheet receiving surfaces, of a plurality of folding blades, shafts on which said blades are mounted, gears on the shafts, an internally toothed ring with which said gears are in mesh, bearing for the shafts, and means for holding the shafts against centrifugal force developed by the rapid rotation of the carrier.

6. The combination with a rotary carrier 85 having a plurality of sheet receiving surfaces, of a plurality of folding blades, shafts on which the blades are mounted, bearings for the shafts located in the carrier head, an internally toothed ring located alongside the carrier, gears on the shafts in mesh with the ring, and coöperating means carried on the shafts and ring for holding the shafts against the centrifugal force developed by the rapid rotation of the carrier.

7. The combination with a rotary sheet carrier having a plurality of sheet receiving surfaces, of a plurality of folding blades, shafts on which the blades are mounted, bearings for the shafts in one of the heads of the carrier, an internally toothed ring located beyond the end of the carrier, gears mounted on the shafts and in mesh with the ring, a circular bearer for each shaft the

diameter of said bearers being equal to the diameter of the pitch circle of the gears, and a circular track with which the bearers coöperate, the diameter of the circle in-
5 closed by said track corresponding to the diameter of the pitch circle of the internally toothed ring.

8. In a rotary folder, a folding cylinder, a rotary tucker blade journaled therein, an internal gear beside one end of the cylinder, a gear on the tucker blade shaft meshing with the internal gear, and bearers beside the said gears for keeping them in pitch-line mesh.

15 9. In a rotary folder, a folding cylinder, a rotary tucker blade journaled therein, an

internal gear beside one end of the cylinder, a gear on the tucker blade shaft meshing with said internal gear, an annular bearer beside and at the pitch line of the annular gear, and a circular bearer beside and at the pitch line of the tucker blade gear, engag-
20 ing the annular bearer for the purpose specified.

In testimony whereof, I have hereunto 25 set my hand, in the presence of two sub-scribing witnesses.

LOUIS A. SCHMIDT.
